United States Patent Office

Des. 193,137
Patented July 3, 1962

193,137

WHEEL

Ronald A. Geisler, 12531 Caswell Ave.,
Los Angeles 66, Calif.

Filed Sept. 11, 1961, Ser. No. 66,715

Term of patent 14 years

(Cl. D14—30)

Fig. 1.

Fig. 2.

Fig. 3.

FIGURE 1 is a front perspective view of a wheel, showing my new design;

FIGURE 2 is a side elevational view thereof; and

FIGURE 3 is a front elevational view thereof.

The characteristic features of my design reside in the face-plate enclosed within the outer rim as best shown in FIGS. 1 and 2.

I claim:

The ornamental design for a wheel, as shown and described.
